UNITED STATES PATENT OFFICE.

FRANK B. HOWELL, OF DETROIT, MICHIGAN, ASSIGNOR TO THE AMERICAN RADIATOR COMPANY, OF NEW JERSEY.

DESIGN FOR A SECTION FOR STEAM-BOILERS.

SPECIFICATION forming part of Design No. 33,784, dated December 25, 1900.

Application filed November 27, 1900. Serial No. 37,933. Term of patent 14 years.

To all whom it may concern:

Be it known that I, FRANK B. HOWELL, a citizen of the United States of America, residing at Detroit, county of Wayne, and State of Michigan, have invented and produced a new and original Design for Sections for Steam-Boilers, of which the following is a specification, reference being had to the accompanying drawings, forming a part thereof, and in

10 which—

Figure 1 is a front elevation of the design, and Fig. 2 is a side or edge elevation thereof.

As shown in the drawings, the leading or material features of the design consist of a 15 modified arch form, the side members A B of the arch being substantially straight and parallel through their upper portions and inclined toward each other and somewhat widened at their lower ends, and the cross 20 member or crown C of the arch having round-

ed ends which project beyond the outer faces of the side members A B, its lower margin being straight and its upper margin curved upwardly from end to end.

Minor features of the design are the outward inclination from each edge of the side and top faces of the arch and a circular aperture transversely through the crown C of the arch and through the lower or widened portion of each of its side members A B.

25 I claim as my invention—

The design for a section for a steam-boiler, as herein shown and described.

In testimony whereof I have signed my name to this specification in the presence of 35 two subscribing witnesses.

FRANK B. HOWELL.

Witnesses:

CLARENCE CARPENTER,
GEO. G. DIXON.
